CLAIM

The ornamental design for a water craft, as shown and described.

DESCRIPTION

FIG. 1 is a top perspective view of a water craft showing my new design;

FIG. 2 is a top plan view thereof;

FIG. 3 is a side elevational view thereof, the opposite side elevational view being a mirror image of that shown;

FIG. 4 is a front elevational view thereof;

FIG. 5 is a rear elevational view thereof;

FIG. 6 is a bottom plan view thereof;

FIG. 7 is a cross sectional view thereof taken along the line 7—7 of FIG. 2;

FIG. 8 is a cross sectional view thereof taken along the line 8—8 of FIG. 2;

FIG. 9 is a cross sectional view thereof taken along the line 9—9 of FIG. 2; and,

FIG. 10 is a cross sectional view thereof taken along the line 10—10 of FIG. 2.

Fig. 7.

Fig. 8.

Fig. 9.

Fig. 10.
